UNITED STATES PATENT OFFICE

151,629

DESIGN FOR A COMBINED LAMPPOST
AND LAMPEddy Lamb and Clair D. Freeman,
Los Angeles, Calif.

Application January 3, 1947, Serial No. 135,934

Term of patent 7 years

(Cl. D48—31)

To all whom it may concern:

Be it known that we, Eddy Lamb and Clair D. Freeman, both citizens of the United States, residing at 1131 No. Larrabee Street, Los Angeles 46, in the county of Los Angeles and State of California, have invented a new, original and ornamental Design for a Combined Lamppost and Lamp, of which the following is a specification, reference being had to the accompanying drawing, forming a part thereof.

Figure 1 is a front elevational view of a combined lamppost and lamp, showing our new design.

Figure 2 is a side elevational view thereof.

We claim:

The ornamental design for a combined lamppost and lamp substantially as shown.

EDDY LAMB.
CLAIR D. FREEMAN.
